UNITED STATES PATENT OFFICE.

EDGAR ROUSE SUTCLIFFE, OF LEIGH, ENGLAND.

PRESS FOR THE PRODUCTION OF BRICKS, BRIQUETTES, BLOCKS, AND THE LIKE.

Application filed October 4, 1922. Serial No. 592,317.

To all whom it may concern:

Be it known that I, EDGAR ROUSE SUTCLIFFE, a subject of the King of Great Britain and Ireland, residing at Leigh, Lancashire, England, have invented certain new and useful Improvements Relating to Presses for the Production of Bricks, Briquettes, Blocks, and the like, of which the following is a specification.

10. This invention relates to presses of the rotating mould table type for the production of bricks, briquettes, blocks and the like from concrete, clay or other materials or mixtures capable of being moulded by pressure.

The invention especially relates to the press of the construction and operation described in the specification of the prior Patent No. 744,430 November 17, 1903.

20. The invention has among its objects to improve the construction of the press and to adapt the press for the development of higher powers and speeds or for the production of bricks, briquettes or blocks of 25 relatively large size, or bricks, briquettes or blocks compressed to a relatively high pressure.

The invention has also among its objects to combine two presses for being fed with 30 the material or mixture to be compressed from a single pan disposed between them.

According to the invention I provide means to balance the weight or part of the weight of the connected cross heads or the 35 lower cross head.

According to the invention, moreover, means are provided for pushing the ejected brick, briquette or block from the top of the mould table after it has been raised from 40 the mould.

The invention comprises the constructional features which are hereinafter described.

The invention is illustrated by way of example in the accompanying drawings 45 which represent a press of a construction generally resembling that described in the specification of the said prior patent, involving similar mechanism for operating

the plunger, for ejecting the brick, briquette or block, and for causing the rotation of the 50 mould table.

Figure 1 represents a side elevation of the press partly in section through the centrally disposed feeding pan.

Figure 2 is a corresponding side elevation partly in section.

Figure 3 is a further side elevation in which the mechanism is indicated for pushing the brick, briquette or block from the top of the mould table after it has been 60 raised from the mould.

Figure 4 is a corresponding front elevation, and

Figure 5 a corresponding plan.

In carrying the invention into effect in 65 its application to a press of the kind described in the specification of the said prior patent, I provide the plunger i^1 by means of which the compressed bricks, briquettes or blocks are forced out of the moulds in 70 the rotating mould table i , to be operable by means of a lever d deriving movement from a cam a that is mounted upon a shaft b disposed beneath the first motion shaft c and parallel with it. Such a construction 75 permits of a straight lever or a substantially straight lever which is also relatively short to be used and avoids the necessity of the use of the bell crank lever employed in the construction of the prior patent referred 80 to. Moreover the cam a may be provided as an eccentrically disposed box cam having a circular cam groove which involves a practical advantage in construction as well as in the operation of the machine.

It will be understood that the shaft b upon which the operating cam a is mounted has imparted to it a movement at the same speed as that of the main shaft e through gearing from the first motion shaft c . Thus the movement is simultaneously imparted to the main shaft e and to the cam shaft b by which the ejecting plunger i^1 is operated in the manner described.

As illustrated in the drawings and more 95 particularly in Figures 4 and 5, two presses

are provided having their mould tables respectively disposed on the right hand side and on the left hand side, so that the mould tables may be brought into juxtaposition 5 and the respective horizontally disposed shafts brought into alignment, and thus a single first motion shaft *c* may be employed for both presses whereby a single drive may be applied from one end of the first motion 10 shaft.

Such a construction permits of a single pan *o* being disposed between the respective presses and of mechanism being provided to impart movement to radial rakes or stirrers *o*¹ within the pan by means deriving 15 movement from the first motion shaft *c* of the combined presses. These means may conveniently consist of a vertical spindle *p* passing through a central vertical tubular boss *o*² of the pan and upon the upper end of this spindle a boss *o*³ may be mounted to which the rakes or stirrers *o*¹ may be connected. Movement is advantageously imparted to the vertical spindle *p* by bevel 20 gear from a counter shaft *q* whose movement is effected by means of bevel gear from a spindle *q*¹ driven by belt and pulleys from the first motion shaft *c*. The pan *o* is supported between the press frames by means 25 of a supporting frame *o*⁴ and is otherwise provided as is usual excepting that it is adapted to supply the material to be compressed to the two mould tables. Any other mechanism may be provided for imparting 30 a rotary movement to the rakes or stirrers *o*¹ of the feeding pan.

It will be understood that movement is imparted from the first motion shaft *c* to the respective presses through a toothed pinion 1 engaging the gear wheel 2 on the main shaft *e* and the toothed wheel 3 on the cam shaft *b*. Movement is imparted for the operation of compression by means such as described in the specification of the prior 45 patent whereby no stress is imposed upon the mould table during the compressing operation so that thus only the dead weight of the connected cross heads *h* *h*¹ rests upon the mould table no matter what the degree 50 of compression exercised.

It will be understood that the movements involved in the compression within the mould, the ejection of the brick, briquette or block, and the partial rotation of the 55 mould table in the succession of operations of the press, are effected in the manner described in the specification of the prior patent aforesaid.

According to the invention moreover 60 means are provided to balance the weight or part of the weight of the connected cross heads *h* *h*¹ or of the lower cross head *h*. Such means consist of a weighted lever *f* mounted beneath the main part of each of 65 the press frames, the shorter arm *f*¹ of

which lever is pivotally connected to symmetrical arms *g* which are advantageously provided integral with the lower cross head *h*, the longer arm of the lever being provided with a weight *f*² which conveniently 70 may be adapted to be varied in position as may be required.

The cam lever *d* as well as the weighted lever *f* are mounted beneath the bottom part of the main frame *r* of the respective presses, 75 being advantageously mounted within a cavity *s* provided in position beneath that in which the presses are to be mounted. For this purpose each of the shafts *f*⁴ upon which the cam levers are mounted are supported by two frame members *t* of symmetrical shape and these may be mounted upon bosses or base plates *t*¹ *t*² and the centrally disposed base plate *t*¹ may be utilized for mounting the bevel gear and spindle *q* *q*¹ through which movement is imparted to the vertical spindle *p* as aforesaid.

The respective weighted levers *f* are disposed in the plane of the cross heads *h* *h*¹ and are advantageously carried from the 90 main frame *r* of the machine within brackets *f*³.

According to the invention, moreover, improved means are provided for pushing the ejected brick, briquette or block from the top of the mould table *i* after it has been raised from the mould. These means comprise a cam *k* on the main shaft *e* and mechanism by which movement is imparted from the cam *k* to a sliding pusher block 100 *m*². This sliding block *m*² is advantageously mounted upon a guide rod *n* or upon guides, and the rod *n* may be supported at one end from the press frame and at the other by means of a rod *n*¹, so that the 105 block may move from the position indicated in Figures 1, 3 and 5 immediately above the table and adjacent that into which the ejected brick, briquette or block is raised, into a position beyond the table 110 and to the same radial line so that thus the pusher block *m*² will force the ejected block radially outwards into a position on to a conveyor or table in front of the mould table *i*. Thus the pusher block *m*² does not 115 slide upon the face of the rotating mould table *i*.

The cam *k* from which the movement of the pusher block *m*² is derived is advantageously mounted upon the outer end of 120 the respective main shafts *e* from which movement is imparted by the cam lever *l*¹ to a link *m* whose opposite end is connected to the short arm *m*¹ mounted upon 125 a horizontal spindle *m*³ disposed in position above the respective mould table *i* and carried in suitable brackets from the frame. At the opposite end of this spindle *m*³ another longer arm *m*⁴ is mounted to extend downwardly, at the lower end of which 130

it is connected by means of a link m^5 with the sliding pusher block m^2 . It will be understood that the operating cam k and the ejecting mechanism are so provided that 5 the movement of the pusher block synchronises with the operation of the ejecting plunger.

I claim:

1. A press of the rotating mould table 10 type for the production of bricks, briquettes and the like by compression effected on the operation of toggle gear operating between cross heads carried respectively above and below the mould table, and comprising in combination a power shaft, an 15 ejecting plunger, means for causing the movement of the ejecting plunger consisting of a cam mounted upon a shaft disposed beneath the first mentioned shaft, 20 and a cam lever, one end of which is connected to the ejecting plunger, said cam lever being disposed beneath the main part of the press frame and being operated by the said cam, substantially as described.

2. A press of the rotating mould table 25 type for the production of bricks, briquettes and the like by compression effected on the operation of toggle gear operating between crossheads carried respectively 30 above and below the mould table, and comprising in combination a power shaft, an ejecting plunger, means for causing the movement of the ejecting plunger consisting of a box cam having a circular cam 35 groove, said box cam being mounted upon a second shaft disposed beneath the first mentioned shaft, and a cam lever, one end of which is connected to the ejecting plunger, said cam lever being disposed beneath 40 the main part of the press frame and being operated by the said cam, substantially as described.

3. A press of the rotating mould table 45 type for the production of bricks, briquettes and the like by compression effected on the operation of toggle gear operating between crossheads carried respectively above and below the mould table, and comprising in combination a power shaft, an 50 ejecting plunger, means for causing the movement of the ejecting plunger consisting of a cam mounted upon a second shaft disposed beneath the first mentioned shaft, and a cam lever pivotally mounted in a middle 55 position beneath the frame of the press, one end of which lever is operated by the cam and the other end of which is connected to the ejecting plunger, substantially as described.

4. A press of the rotating mould table 60 type for the production of bricks, briquettes and the like by compression effected on the operation of toggle gear operating between crossheads carried respectively above and below the mould table, comprising means for 65

balancing the weight or part of the weight of the connected crossheads consisting of a weighted lever, substantially as described.

5. A press of the rotating mould table 70 type for the production of bricks, briquettes and the like by compression effected on the operation of toggle gear operating between crossheads carried respectively above and below the mould table, comprising means for balancing the weight or part of the 75 weight of the connected crossheads consisting of a weighted lever pivotally mounted in position beneath the main part of the press frame, the shorter arm of which lever is pivotally connected to the lower crosshead and the longer arm of which carries a weight, substantially as described.

6. A press of the rotating mould table 80 type for the production of bricks, briquettes and the like by compression effected on the 85 operation of toggle gear operating between crossheads carried respectively above and below the mould table, comprising mechanism for pushing the ejected brick, briquette or block from the top of the mould table on being raised from the mould, said mechanism consisting of a sliding pusher block, means by which said pusher block is adapted to slide outwardly from a position above the mould table, and mechanism deriving movement from the press gear by which the pusher block is moved in synchronism with the ejecting plunger, substantially as described.

7. A press of the rotating mould table 90 type for the production of bricks, briquettes and the like by compression effected on the 95 operation of toggle gear operating between crossheads carried respectively above and below the mould table, comprising mechanism for pushing the ejected brick, briquette or block from the top of the mould table on being raised from the mould, said mechanism consisting of a pusher block, members upon which said pusher block is adapted to slide outwardly from a position above the mould table, a cam deriving movement from the press gear, a cam lever, means for imparting movement from said cam lever to said pusher block comprising a lever and links by which the pusher block is moved in synchronism with the movement of the ejecting plunger, substantially as described.

8. In presses for the production of bricks, 100 briquettes, blocks and the like of the type indicated, the combination of two presses juxtaposed so that the connected cross heads are situated outwardly and in line, and the provision of a common feeding pan for the respective mould tables of the presses, substantially as hereinbefore described.

9. In presses for the production of bricks, 105 briquettes, blocks and the like combined as specified in claim 8, in combination, means 110 for imparting movement to radial rakes 115

within the feeding pan comprising a vertical shaft extending upwardly through the feeding pan, a boss applied on the upper end of the said spindle, radial rakes connected to the said boss, and means by which movement is imparted to the said vertical spindle from the gear of the combined presses, substantially as described.

10. A press of the rotating mould table type for the production of bricks, briquettes and the like by compression effected on the operation of toggle gear operating between

cross heads carried respectively above and below the mould table, comprising a feeding pan disposed above the mould table and means for imparting movement to radial rakes within the said feeding pan, consisting of a vertical shaft deriving movement from the press gear, said shaft extending upwardly through the feeding pan and having a boss at its upper end and radial rakes secured to the said boss, substantially as described. 15 20

EDGAR ROUSE SUTCLIFFE.
